UNITED STATES PATENT OFFICE.

OSCAR LENDING, OF BROOKLYN, NEW YORK.

COMBINED HAND BAG AND CAMERA.

Application filed November 10, 1924. Serial No. 749,079.

To all whom it may concern:

Be it known that I, OSCAR LENDING, a citizen of Poland, and resident of the borough of Brooklyn, in the county of Kings, 5 city and State of New York, have invented certain new and useful Combined Hand Bags and Cameras, of which the following is a specification.

This invention relates to ladies' hand bags 10 arranged as a vanity case to carry toilet articles and the like, and it is the object of the invention to arrange said bags as a combined hand bag and camera carrier, and to provide a bag of this character wherein access 15 may be had to the toilet or other articles while maintaining the camera enclosed, or the camera may be exposed for the purpose of taking pictures while the article carrier is maintained closed.

20 In the drawing accompanying and forming a part of this specification I have illustrated an embodiment of the invention wherein Figure 1 is a perspective view of the combined hand bag and camera carrier 25 showing the same in closed condition and looking at one end and side thereof.

Figure 2 is a perspective view, looking at the inside thereof, of an enclosing and carrier back or fold for the bag.

30 Figure 3 is a perspective view looking at one end and two sides of the enclosing fold or back adjusted to expose the camera for the purpose of taking a picture while maintaining the article carrier of the bag closed.

35 Figure 4 is a view similar to Figure 3, but showing the enclosing fold or back adjusted to expose the article carrier for the purpose of getting access to articles in said carrier; and

40 Figure 5 is a detail sectional view of the camera and article carrier and showing means for releasably connecting the camera to the article carrier.

Similar characters of reference designate 45 like parts throughout the different views of the drawing.

In carrying out the embodiment of the invention illustrated in the drawing there is provided an elongated body or back, shown 50 in a general way at 6, preferably of one piece and of suitable material, such as leather or fabric, which may have a lining or facing applied to the inner surface as viewed in Figure 2, and adapted to be folded as at 7, 8, 9 and 10, the one end portion being slitted longitudinally and substantially mid-

way between the side edges, as at 11, to adjacent the fold or crease 9 to arrange said end of the back with a pair of parallel flaps 12 and 13. The opposite end of the back is 60 arranged as a main flap 14 having a portion at the extremity cut away, as at 15, said end of the back is also arranged with an auxiliary flap 16 stitched at one end to the inner surface of the back adjacent the fold 8, 65 said flap being of a length to extend beyond the cutaway portion 15 of the main flap 14, as clearly shown in Figure 2 for a purpose to be hereinafter described.

A casing 17 in the form of a receptacle 70 open at the end or top is secured at the bottom by an adhesive or otherwise to the intermediate portion of the back with one side flush with a side marginal portion of the back, said casing being of a length to extend between the folds or creases 8, 9 and 75 of a width substantially of the flap 13 which flap is adapted to serve as a cover for the opening of the casing. The casing is of a height substantially of the area between the 80 folds or creases 7, 8, and 9, 10. The receptacle 17 is adapted to serve as a vanity case to carry toilet articles, and also to carry a purse, handkerchief or the like. The flap 13 may carry a mirror 18 on the inner surface 85 thereof.

As stated, it is an object of the invention to provide a combined hand bag and camera carrier. For this purpose there is provided a camera of conventional form and indicated in a general way at 19, the same being substantially of the same conformation and size as the casing 17 to be enclosed and carried within the flap portions 12, 16. The camera may be permanently adapted to the 90 intermediate portion of the back or fold between the creases 8, 9, but it is preferably releasably mounted in the bag for which purpose it has a snap fastener connection 95 with the casing 17, as shown at 20, Figure 100 5, one member of the snap fastener being carried by the camera and the other by the casing 17. By this arrangement the camera may be released from the casing 17, as shown in dotted lines in Figure 3, for the purpose of facilitating the inserting and removing of a film from the camera. As is 105 obvious the flaps may be folded around and enclose the casing and camera and are releasably secured in closed position by snap fasteners, one member of which is secured 110 to the flaps 12, 13, as shown at 21, 22 while

the other members are secured to the flaps 14, 16, as shown at 23, 24.

To enclose the casing and camera in the fold or back the flaps 12, 13 are engaged about the casing and camera, the flap 13 serving as a closure for the opening in the casing, when the flaps 14, 16 are folded over the flaps 12, 13 and secured in such position by the snap fasteners. Should it be desired to get access to the casing 17 the main flap 14 is released from the flap 13 when said flaps may be adjusted to the positions indicated in Figure 4 and without exposing the camera enclosed by the flaps 12, 15 16, said latter flaps being retained in enclosing position. Should it be desired to get access to the camera for the purpose of exposing the lens 25 and finder 26 for the purpose of taking a picture the auxiliary flap 16 is released from the flap 12 and the latter adjusted to the position indicated in Figure 3 without releasing the flaps 14, 13, this being readily accomplished due to the cutting away of the portion of the flap 14 at 15.

To facilitate the carrying of the device it is arranged with a hand grip upon the exterior of the bag, said grip comprising a strap 27 connected at opposite ends to rings 28 movably attached to the bag, as at 29. By the releasable mounting of the camera it will be obvious that another article, such as another casing 17, may be substituted therefor and enclosed within the fold or back.

Having thus described my invention I claim:

1. In a hand bag, a back arranged with co-operating closure flaps at opposite ends, a pair of sidewise arranged casings intermediate the flap portions of the back and over which the flap portions are adapted to be closed, and said flaps adapted to be released independently of each other whereby access may be had to either of the casings.

2. In a hand bag, a back having parallelly arranged flaps at one end and the opposite end arranged with a main flap and an

auxiliary flap, and said flaps arranged with releasable securing means, and a pair of sidewise arranged casings intermediate the flaps of the back, one of which casings is fixed to the back and the other casing releasably connected to said fixed casing, and over which casings the flaps are adapted to be closed.

3. In a hand bag, an open end article carrying receptacle, a camera juxtaposed to said receptacle, and means to be folded around and enclose said receptacle and camera arranged with independently releasable closure means whereby access may be had to the receptacle and the camera enclosed by said means, or the camera exposed for the purpose of taking a picture while maintaining the receptacle closed.

4. In a hand bag, an open end receptacle, a camera arranged in sidewise relation to said receptacle, a fold to be folded around said receptacle and camera, one end of the fold being slitted longitudinally to provide parallel flap portions and the opposite end arranged as a main flap and an auxiliary flap to be folded over the parallel flaps and independently and releasably secured thereto, said main flap being adapted to be releasable to get access to the receptacle, and the auxiliary flap released independently of the main flap for exposing of the lens of the camera for taking a picture, and a hand grip connected to the outer side of the fold.

5. In a hand bag, a back arranged with a pair of flaps at opposite ends and an intermediate section, juxtaposed articles carried by the intermediate section of the back and over which the flaps are adapted to be folded to serve as closures therefor, and means to releasably retain said flap portions in closed condition and adapted to be separately released.

Signed at New York city in the county of New York and State of New York, this 24th day of October, 1924.

OSCAR LENDING.
